UNITED STATES PATENT OFFICE.

LOUIS T. FREDERICK, OF WILKINSBURG, PENNSYLVANIA, ASSIGNOR TO WESTINGHOUSE ELECTRIC & MANUFACTURING COMPANY, A CORPORATION OF PENNSYLVANIA.

METHOD OF AND APPARATUS FOR IMPREGNATING MATERIAL.

1,414,462.

Specification of Letters Patent.

Patented May 2, 1922.

Application filed May 6, 1919. Serial No. 295,192.

To all whom it may concern:

Be it known that I, LOUIS T. FREDERICK, a citizen of the United States, and a resident of Wilkinsburg, in the county of Allegheny and State of Pennsylvania, have invented a new and useful Improvement in Methods of and Apparatus for Impregnating Material, of which the following is a specification.

10 My invention relates to methods of, and apparatus for, impregnating fibrous material, and it has, for its primary object, the impregnation of fibrous sheet material in such manner that the speed of the operation 15 and the degree of impregnation may be increased to a considerable extent, as compared with the methods heretofore employed and the operation to be performed, with less difficulty.

20 My invention has particular relation to a method of impregnating fibrous sheet material, such as paper, with a binder in a liquid state which may be subsequently dried to an intermediate state and may then be 25 hardened, by a further application of heat, to a substantially insoluble and infusible state. My invention contemplates the employment of a phenolic condensation product as a binder but other similar binders may 30 be employed.

Heretofore, a method employed for impregnating paper with a phenolic condensation product consisted in immersing the paper in a solution of a phenolic condensation 35 product, after which the paper was subjected to pressure to remove the excess liquid and then dried. Paper or similar sheet material, treated in this manner, usually gains approximately 60% in weight. In view of 40 this, one object of my invention is to provide apparatus which may be employed in impregnating sheet material, such as paper, with a binder in such manner that the employment of a solvent in the binder may be 45 avoided.

A still further object of my invention is the provision of a method by which fibrous material may be impregnated and in which pressure may be employed to hasten the impregnating process.

With these and other objects in view, my invention will be more fully described, illustrated in the drawings, in the several views of which corresponding numerals indicate

like parts, and then particularly pointed out 55 in the claims.

In the drawings, Fig. 1 is a side view, partly in section and partly in elevation, of a machine which may be employed in impregnating fibrous material in accordance 60 with my invention, and Fig. 2 is a plan view of the machine shown in Fig. 1.

In practising my invention, I may employ a machine, such as shown in Figs. 1 and 2, which comprises a plurality of upright 65 frame members 1 to which may be secured a plurality of horizontal beams 2 by any suitable means, such as angle irons 3. Shafts 4 and 5 may be mounted, one at each side of the machine, upon bearing members 6 70 supported by the horizontal beams 2. Each of the shafts 4 and 5 may have rigidly mounted thereon corresponding sprocket wheels 7 which may be operatively connected by a chain 8 which is twisted so that the 75 sprocket wheels and, consequently, the shafts shall rotate in opposite directions. A plurality of similar sprocket wheels 9 may be mounted upon each of the shafts 4 and 5 near the bearing members 6 and each of 80 these sprocket wheels may support a chain 10 secured, at one end, to a liquid-retaining tank 11 and, at its other end, to a suitable counter weight 12.

As a means for raising and lowering the 85 tank 11 I may provide a suitable sprocket wheel 13 rigidly mounted upon the shaft 4 and connected, by a chain 14, to a sprocket wheel 15 mounted upon a shaft 16 which also carries a worm wheel 17 and which is supported by a bearing member 18 mounted upon one of a plurality of horizontal beams 19 disposed at the sides of the machine. A shaft 20, which is provided, at one end, with a worm which engages the worm wheel 17, 95 is supported by the bearing member 18 and has a hand wheel 21 mounted upon its opposite end. It will be apparent from the above description that the tank 11 may be raised or lowered, as desired, by operating the 100 hand wheel 21.

A plurality of rolls 22, 23, 24, 25 and 26 may be suspended within the tank 11 by mounting them upon suitable frame members 27 suspended, at each side of the machine, 105 from the horizontal beams 2. The rolls 22 and 23, 24 and 25 constitute two pairs of pressure rolls and the roll 26 serves as a

guide roll. The roll 24 may be provided with a pressure-exerting means which may comprise springs 28 so mounted in suitable openings in the frame members 27 as to engage the bearings of the roll 24 and the walls of the openings in the frame members. The upper pressure roll 22 may be provided with means for adjustment relative to the roll 23 as indicated at 29. The roll 23 may have mounted upon one end of its shaft, a plurality of sprocket wheels 30, one of which is connected by a chain 31 to a similar sprocket wheel 32 mounted upon the corresponding end of the shaft of the lower pressure roll 25. The lower pressure roll 25 may have another sprocket wheel 33 mounted upon the opposite end of its shaft which may be connected, by a chain 34, to a sprocket wheel 35 mounted upon the corresponding end of the shaft of the guide roll 26.

Material which is to be treated in the machine may be drawn from a suitable supply roll 36 and guided by a suitably mounted idler roll 37 to another guide roll 38 which is supported above the tank 11 by the horizontal beams 19. The material may be led from the guide roll 38 into the tank and beneath the guide roll 26 and out of the tank between the pressure rolls supported therein to a drying tower 39 which may be supported by the frame members 1. A suitable idler roll 40 may be mounted within the tower 39, and the material may be drawn over it and guided to a driven roll 41 mounted upon the beams 19 and thence over another guide roll 42, also mounted upon the beams 19, to a receiving roll 43, supported by any suitable means, as indicated at 44.

As a driving means for the various rolls employed in the machine, I may utilize an electric motor 45 which is shown in Fig. 2. The motor 45 may be connected, through any suitable drive mechanism, to a sprocket wheel 46 which is connected, by a drive chain 47, to a similar sprocket wheel 48 mounted upon the shaft 49 of the roll 41. The shaft 49 may also have mounted thereon a suitable gear wheel 50 adapted to mesh with a gear wheel 51 mounted upon the shaft of the roll 42. A sprocket wheel 52 may be mounted upon the opposite end of the shaft 49 and may be connected, by a drive chain 53, to one of the sprocket wheels 30 of the pressure roll 23. A drive connection is thus established between the motor 45 and the rolls disposed in the tank 11. In order to provide a driving means for the receiving roll 43, a sprocket wheel 54 may be mounted upon the shaft 49 and may be connected, by a chain 55, to a sprocket wheel 56 mounted upon a shaft 58 communicating with the shaft of the receiving roll 43 through a suitable chuck member 57. The shaft 58 communicating with the receiving roll may be provided with a clutch mech-

anism 59 which may be employed to regulate the speed of the receiving roll.

In operating the machine above described, care should be taken that the impregnating liquid contained in the tank 11 shall be maintained at a level substantially represented by the pressure-exerting surfaces of the upper pressure rolls 22 and 23. This may be maintained by slight adjustment of the position of the tank from time to time or by addition of impregnating liquid as it is removed by the material. Sheet material, which is to be impregnated, may be led from the supply roll 36 to the roll 38 and may then be drawn into the impregnating tank 11 under the guide roll 26. The material is led between the lower pressure rolls 24 and 25 which exert a constant pressure on both sides of the material and from there it is led between the upper pressure rolls 22 and 23 which may be adjusted to exert any desired pressure. The material emerges from the liquid to be drawn into the drying tower 39 where sufficient heat is applied to thoroughly dry the impregnating material. The material is led over the idler roll 40 and out of the tower to the guide rolls 41 and 42 and then to the receiving roll 43. By means of the clutch mechanism 59, the speed of the receiving roll 43 may be reduced so that a more compact roll of material may be obtained.

It should be noted that all the rolls and mandrels employed in the machine are driven from a main drive shaft and are, therefore, always rotated at the same speed, with the exception of the receiving roll which is also driven at the same speed except when it is necessary to run it more slowly to obtain a more compact roll. Furthermore, by employing a plurality of pressure rolls in the impregnating liquid, thorough impregnation is obtained and, by partially immersing the upper rolls, any possibility of the impregnating liquid becoming gummed on the rolls is avoided. Utilization of the pressure rolls in such manner also accelerates the operation of impregnation and renders unnecessary the employment of a solvent in a binder of relatively high viscosity to obtain thorough impregnation.

I have found that heavier sheet material may be employed than was possible heretofore on account of the higher degree of impregnation obtained by the method above described. The liquid is preferably employed cold and, on account of this, together with the omission of the use of a solvent, the retaining tank may be open at its top which facilitates the work to some extent, as the upper pressure rolls are always accessible without stopping the operation of the machine. Moreover, by employing a tank which is open at its top, the state of the impregnating liquid may be kept under observation

and the necessary height of liquid maintained with ease.

Although I have specifically described a machine for, and method of, impregnating fibrous material in accordance with my invention, it is obvious that minor changes may be made, both in the process and in the apparatus, without departing from the spirit of my invention and I desire, therefore, that 10 no limitations shall be imposed except such as are indicated in the appended claims.

I claim as my invention:

1. In an apparatus for impregnating fibrous material, means for drawing the material through a liquid impregnating agent, means for forcing the liquid into the material and means for removing excess liquid at the surface thereof.

2. In an apparatus for impregnating fibrous material, means for drawing the material through a liquid impregnating agent, means for exerting a pressure upon both sides of the material beneath the surface of the liquid and means for applying additional pressure to the material at the surface of the liquid.

3. In an apparatus for impregnating fibrous material, means for drawing the material through a liquid impregnating agent, means for exerting a pressure upon both sides of the material beneath the surface of the liquid, means for applying additional pressure to the material at the surface of the liquid and means for varying the pressure.

4. In an apparatus for impregnating fibrous material, means for drawing the material through a liquid impregnating agent, means for exerting a pressure upon both sides of the material beneath the surface of the

the liquid, means for applying additional 40 pressure to the material at the surface of the liquid, means for varying the pressure and means for drying the impregnated material after it emerges from the liquid.

5. In an apparatus for impregnating 45 fibrous sheet material, the combination of a tank having an open top and adapted to retain an impregnating liquid, two pairs of rolls supported within the tank, the rolls of one pair being relatively adjustable, a drying tower disposed above the tank, means for leading sheet material to the rolls in the tank and through the tower, and means for receiving the material after it has been dried.

6. In an apparatus for impregnating 50 fibrous sheet material, the combination of a tank having an open top and adapted to retain an impregnating liquid, two pairs of rolls supported within the tank, the rolls of one pair being relatively adjustable, a drying 55 tower disposed above the tank, means for leading sheet material to the rolls in the tank and through the tower, a means for receiving the material after it has been dried and means for controlling the speed of rotation of the said receiving means.

7. A method of impregnating sheet material that comprises passing the sheet material through a bath of impregnating liquid, applying pressure to the material while it is 70 immersed, applying additional pressure at the surface of the bath, drying the material and winding it about a receiving mandrel.

In testimony whereof, I have hereunto subscribed my name this 18th day of April, 75 1919.

LOUIS T. FREDERICK.
